MOUNTING FOR REFLECTOR BUTTONS OR
THE LIKE

Warren H. Barton, Staten Island, N. Y.

Application August 22, 1936, Serial No. 97,370

4 Claims. (Cl. 88—82)

This invention relates to a mounting which, while not necessarily restricted thereto, is particularly designed for supporting one or more reflector buttons upon a base of sheet or strip material and a method of securing said buttons or the like to the base.

The invention broadly aims to provide simple, inexpensive and effectual means for and a method of securing the reflector buttons or equivalent devices to a base of sheet or strip material so as to provide completed structural units, which are compact, flexible and durable and capable of many and varied uses.

More particularly the means for mounting said reflector buttons or the like comprises a perforated sheet or strip of material constituting a base with a tubular shell snugly fitted within the perforation and protruding beyond one surface of the base, the said shell having an outwardly directed marginal flange engaging the opposite surface of the base together with an expanded retaining element located within the shell beyond the plane from which it protrudes, and forming on the shell an outwardly extended bead which anchors the shell to the base.

As a further feature the invention resides in a method of mounting a reflector button or the like which consists in removing from a base of sheet or strip material a portion thereof so as to leave a perforation, inserting in said perforation a shell having an outwardly directed marginal flange at one end which engages with one surface of the base and with the other end of the shell protruding beyond the other surface and carrying the reflector button, dishing the removed portion of the base, inserting the same into the shell with its marginal edge disposed in a plane beyond the face from which the shell protrudes and with its convex surface disposed rearwardly and then applying pressure to the convex rear surface of said portion to expand the same and form on the shell an outwardly extending bead for anchoring the shell in place and retaining the reflector button within the shell.

With these and other objects in view, the invention is more particularly set forth in the following specification and in the drawing wherein there is disclosed a preferred embodiment, while the claims cover variations which are within the scope of the invention.

In the drawing:

Fig. 1 is a face view of a mounting strip having a plurality of reflector buttons supported thereon in accordance with the invention.

Fig. 2 is an enlarged transverse sectional view

therethrough taken approximately on a plane indicated by the line 2—2 in Fig. 1.

Fig. 3 is a view similar to Fig. 2 illustrating the position of parts immediately prior to the securing of the reflector button and shell in position on the mounting strip.

Referring to the drawing by characters of reference, 10 designates a mounting strip or base of sheet material which may be of any desired length for supporting one or more reflector buttons or other equivalent devices 11 thereon which buttons or devices are provided with an enlarged flange 12 at the rear thereof. The mounting strip or base is formed with a perforation 13 for each button or device 11 to be mounted and a shell 14 is employed for each button or device which in the present instance is of a cross sectional size and configuration conforming to that of the perforation 13. The rear end of the shell is provided with an outwardly directed marginal flange 15 which is adapted to engage with the rear surface 16 of the base 10 in surrounding relation to the perforation when the shell is inserted therein, the forward portion of the shell protruding beyond the forward surface 17 of the base.

As illustrated in the present instance, the forward portion 18 of the shell is of reduced cross sectional size conforming substantially to the contour of the button flange 12 and provided with an inwardly directed forward flange 19 constituting a seat for the outer surface of the button flange 12. Where the device 11 is a reflector button of glass or an equivalent fragile material subject to breakage, a cushioning element such as a felt disk 20 is positioned within the shell in rear of the button or device 11.

The shell is secured or anchored in place by means of a retaining element 21 which is contracted so that the cross sectional size thereof admits of its insertion through the rear end of the shell with its marginal portion disposed in a plane beyond the forward surface 17 of the base 10 after which it is expanded to form on the shell an outwardly extending bead 22 overlying the forward surface of the base thereby securely anchoring the shell in position, while the element 21 further functions to lock and retain the reflector button or device 11 in place.

The method of mounting the reflector button or equivalent device on a base 10 of sheet or strip material, consists preferably in cutting or punching from the base 10 a portion or disk 21 to form a perforation therein, then inserting in said perforation 13 a hollow shell 14 having an outwardly

directed flange 15 at the rear end thereof which engages with the rear surface 16 of the base 10, the forward portion of the shell which carries the button or device 11 protruding beyond the forward surface 17 of the base. Preferably the portion 21 which is cut or punched from the base 10 is utilized as the means for securing or anchoring the shell in place, although within the scope of the invention another similar piece may be utilized, if desired. In any event, the element 21 which corresponds approximately to the cross sectional size of the perforation 13 is dished or buckled so as to reduce its cross sectional size sufficiently to permit of its insertion through the rear end of the shell 14 with its convex surface disposed rearwardly and its marginal edge disposed in a plane beyond that of the forward face 17 of the base, after which pressure is applied to the convex rear face thereof to expand the same and form an outwardly directed marginal bead 22 on the shell, forwardly of the forward face 17 of the base 10 thereby anchoring the shell securely to the base 10. It is, of course, apparent that where the button or device 11 is formed with a flanged rear end 12, as illustrated, and the forward end of the shell with an inwardly directed marginal flange 19, the said button or device is also locked and retained in place by means of the expandible retaining element 21.

From the foregoing it will thus be apparent that a novel means for and method of mounting one or more reflector buttons or equivalent devices has been devised and while in the present disclosure the buttons or devices 11, the shells 14 and the perforations 13, together with the retaining element 21 are disclosed as circular, it is to be understood that the invention is not restricted to this particular shape as it is evident that the configuration of these parts may be varied within the scope of the invention.

What is claimed is:

1. A mounting for a reflector button comprising a base having a perforation, a reflector button mounting shell fitted within the perforation, protruding beyond one surface of the base and having an outwardly directed marginal flange engaging the opposite surface of the base, an out pressed continuous bead formed on the shell beyond the plane of the face from which the shell protrudes defining an internal continuous groove within the shell, and a bendable retaining disk which is capable of an initial contraction radially to a diameter which will pass through the shell and which is normally expanded radially so that its

marginal edge fits within the groove and coacts with the shell bead to anchor the shell to said base.

2. A mounting for a reflector button comprising a base having a perforation, a reflector button mounting shell fitted within the perforation, protruding beyond one surface of the base and having an outwardly directed marginal flange engaging the opposite surface of the base, an out pressed continuous bead formed on the shell beyond the plane of the face from which the shell protrudes defining an internal continuous groove within the shell, and a bendable retaining disk which is capable of an initial contraction radially to a diameter which will pass through the shell and which is normally expanded radially so that its marginal edge fits within the groove and coacts with the shell bead to anchor the shell to said base, said retaining disk also functioning to hold the reflector button within the mounting shell. 20

3. A method of mounting a reflector button on a base, consisting in forming a perforation in the base, inserting into said perforation a hollow shell having an outwardly directed marginal flange at the rear end thereof engaging with the rear surface of the base and with the forward portion of the shell protruding beyond the forward surface of the base, inserting through the rear end of said shell a rearwardly dished retaining element with the marginal edge disposed in a plane beyond the forward surface of the base and applying pressure to said dished element to expand the same and form on the shell an outwardly extended bead for anchoring the shell to the base. 30

4. A method of mounting a reflector button on a base consisting in punching a portion from said base to form a perforation, inserting into said perforation a hollow shell having an outwardly directed flange at the rear end thereof to engage with the rear surface of the base and with the forward portion of the shell protruding beyond the forward surface of the base, dishing the removed portion of the base, inserting the same within the rear end of said shell with the marginal edge thereof disposed in a plane beyond the forward surface of the base and with the convex surface thereof disposed rearwardly and then applying pressure to said removed portion of the base so as to expand the same and form on the shell an outwardly extending bead for anchoring the shell to the base. 40
